WITNESS:

UNITED STATES PATENT OFFICE.

DADI EGGERSTON, OF BALTIMORE, MARYLAND.

COMBUSTION-PROMOTING DEVICE.

Application filed April 18, 1922. Serial No. 554,801.

To all whom it may concern:

Be it known that I, DADI EGGERSTON, a citizen of Iceland, residing at Baltimore, in the county of Baltimore City and State 5 of Maryland, have invented new and useful Improvements in Combustion-Promoting Devices, of which the following is a specification.

This invention relates to improvements in 10 fuel economizers and has for an object the provision of a device which may be installed in the fire box of a furnace, whereby the products of combustion may be more thoroughly consumed and the amount of smoke 15 reduced to a minimum.

Another object of the invention is the provision of a device of the above character which provides an air baffle at the rear end 20 of the fire box to retard the escape of the products of combustion and which in addition, will direct the heat toward the walls of said fire box to more readily promote the generation of steam.

With the above and other objects in view, 25 the invention further includes the following novel features and details of construction, to be hereinafter more fully described, illustrated in the accompanying drawings and pointed out in the appended claim.

In the drawings:—

Figure 1 is a longitudinal sectional view through a portion of a furnace with the invention applied.

Figure 2 is a section on the line 2—2 of 35 Figure 1.

Figure 3 is an enlarged longitudinal vertical section of the invention per se.

Referring in detail to the drawings, wherein like characters of reference denote 40 corresponding parts, the reference character 10 indicates the fire box of the furnace which is herein shown as of the corrugated type and which has its rear end in communication with a smoke flue 11 and its front end 45 provided with a burner 12 of any suitable type.

The invention which is designed to supply air to the interior of the fire box comprises a head 13 which is formed by a pair of 50 hollow conical members 14 and 15. These hollow conical members have their bases surrounded by flanges 16 for the passage of

bolts 17 by means of which the members are secured together. The head 13 is supported upon a suitable bracket 18 arranged within 55 the fire box and one section of the head, for example the section 15 is in communication with one end of an air supply pipe 19 which is controlled by a valve 20. The pipe 19 may lead to any suitable source of air supply, such as a compressor or blower, so that 60 air may be supplied under pressure to the interior of the head 13.

The air so supplied is distributed within the fire box and for this purpose each section 14 and 15 of the head 13 is provided with escape openings 21, the shape of the head and the positions of these openings being such as to direct the air outwardly 70 against the walls of the fire box for mixture with the products of combustion and thus facilitate the consumption of the gases and reduce the consumption of fuel. In addition, the air escaping from the openings 21 forces the products of combustion toward 75 the walls of the fire box to more readily promote the generation of steam. The arrangement of the openings 21 of the section 15 of the head is such that a greater amount of air escapes through this section than through 80 the section 14 which is located nearer the front of the furnace. This increase of the escape of air may be provided for by increasing the number of openings in the section 15 over the section 14, or the openings may be 85 of larger diameter. The result is, that an air baffle will be provided at the rear end of the fire box to retard the escape of the products of combustion and thus permit of a thorough consumption of the steam with a 90 resultant increase of heat. The forward end of the section 14 is provided with a vertically disposed baffle plate 22 which is located between the air escape openings and the burner 12 and acts to deflect the air outward to further aid in distributing the products of combustion toward the walls of the fire box.

The invention is susceptible of various changes in its form, proportions and minor 100 details of construction and the right is herein reserved to make such changes as properly fall within the scope of the appended claim.

Having described the invention what is claimed is:—

In the combination with a furnace having a burner disposed therein in a manner so 5 that it will play its flame horizontally, vertically disposed brackets arranged within said furnace, hollow perforated conical shaped members having their bases secured

together and means supported by the brackets in a manner to be arranged in alignment 10 with the burner, means for supplying air to the members and a deflector plate arranged between the burner and the members as and for the purpose specified.

In testimony whereof I affix my signature.

DADI EGGERSON.
